METAL SPOOL OR BEAM

John M. Wood, Cranston, R. I., assignor to
 Franklin Process Company, Providence, R. I.,
 a corporation of Rhode Island

Application July 8, 1938, Serial No. 218,155

6 Claims. (Cl. 242—123)

This invention relates to an improved metal spool or beam for use in dyeing or other processing treatment of textile and like materials.

One object of the invention is to provide a metal spool or beam of relatively light construction yet capable of withstanding the stress of heavy loads and adapted to hold the material during its treatment with fluids such as dye liquor.

Another object of the invention is to provide a spool or beam of the type indicated having a fixed head at one end and a removable head at its opposite end with means for attaching the latter to the barrel of the spool to provide for compressing the material surrounding the latter.

Another object of the invention is to provide an improved method of manufacturing and assembling the parts of the spool or beam to secure greater economy in the cost of the metal and in the manufacturing operations.

Another object of the invention is to provide an improved method of welding together the parts of the spool to form a substantially integral structure.

Further objects of the improvement are set forth in the following specification which describes a preferred form of construction of the invention, by way of example, as illustrated in the accompanying drawing. In the drawing:

Fig. 1 is a side view of a spool or beam embodying the present invention;

Fig. 2 is an enlarged longitudinal sectional view of the spool taken on its axis and showing its barrel as broken away at the center;

Fig. 3 is a plan view of the fixed end head of the spool showing its center cut away to form a disk for attachment to the opposite end of the spool; and

Fig. 4 is a sectional view of the same illustrating the manner in which the disk is cut from the center of the head to form the opening with a beveled edge and the disk with a beveled rim.

In dyeing and other chemical processing of textiles it is necessary to employ non-corrosive metals for the containers and holders of the material and as a general practice stainless steel is used for such purposes. This metal is very expensive and it is therefore desirable to economize in its use wherever possible. As a feature of the present invention, therefore, the present spool or beam is designed to avoid waste in cutting up the metal sheets from which the spool is constructed by utilizing portions of the metal which are cut away from other parts. Moreover, by an ingenious method of forming and cor-

relating certain of the parts, they may be secured together with a single weld where heretofore it has required two or more welds for the same purpose.

In accordance with modern methods various kinds of textile materials are dyed in masses surrounding perforated tubes or cores and the present spool or beam is especially adapted for dyeing wool tops, although it may be used for other purposes.

Referring to Figs. 1 and 2 of the drawing, the improved spool or beam comprises a cylindrical barrel 2 with flanges or heads at its ends, one head 4 being fixed or stationary on the spool, while the other head 5 is detachable therefrom. The barrel 2 may be constructed from sheet metal rolled into a cylinder with the longitudinal edges of the sheet meeting and secured together by a butt weld. Where the spool is to be used for dyeing or other fluid treatment of the material contained thereon the barrel 2 is perforated with a plurality of small openings 6.

As shown most clearly in Fig. 2 of the drawing, the fixed head 4 of the spool is carried on an annular member or end-closure 7 which is formed with a shouldered flange 8 projecting within the end of the barrel 2 to form a support therefor. The end-closure 7 is provided at its opposite side with a projecting hub or flange 9 surrounding its enlarged bore or opening 10. A radial flange 11 on the end-member or closure 7 projects outwardly beyond the periphery of the barrel 2 and is formed on the inside with a shouldered seat 12 for the head 4. As clearly shown in Fig. 2 the seat 12 has a radial shoulder 13 against which the side of the head 4 abuts, while its lateral shoulder 14 is beveled or inclined inwardly toward the circumference of the barrel 2 where it joins the shouldered portion around which the barrel fits.

It is also to be noted that the head 4 is cut away at the center to form a circular opening with its edge 15 beveled in the opposite direction from the bevel on the seat 14. By this means a V-shaped channel or groove 16 is provided between the circumferential face of the seat 14 and the inner beveled edge 15 of the head 4, the object being to provide for welding the parts together with the metal flowing into the channel 16 to form a strong, secure joint. The weld of the metal is represented at 17 as filling the groove 16 and flowing across its opposite edges to bond the rim of the barrel 2 to its shouldered flange 8 on the end-member 7. In this way one welding operation secures the barrel to the end-mem-

ber 1 and unites the head 4 thereto with a seam extending circumferentially of the several parts.

It has been noted that the central opening in the head 4 is formed with a beveled edge and the beveled edge disk 20 of metal removed from this opening, in the manner indicated in Fig. 4, is utilized for closing the opposite end of the barrel 2 of the spool to conserve the cost of the metal. The edge or rim of the disk 20 being 10 beveled similarly to the edge of the opening in the head 4 adapts its rim to be welded to the interior of the barrel 2 as shown in Fig. 2. The disk 20 is inserted into the barrel 2 and a weld made as indicated at 21 with the metal fused 15 to flow into the groove between the beveled rim of the disk and the inner periphery of the barrel 2.

The disk or closure 20 serves as an internal support for the end of the barrel 2 and also provides means for mounting a threaded tubular member or neck 25 on which the removable head 5 may be supported. One end of the tubular neck 25 is inserted through a central opening 26 in the disk 20, this opening being preferably 25 beveled at one end and the rim of the neck also being beveled to provide a groove or channel for the flux of the weld indicated at 27. The outer portion of the neck 25 is screw-threaded on its exterior to receive a hand-nut 28. As herein illustrated the hand-nut 28 is formed with an 30 interiorly threaded hub 29 with handles 30 projecting radially therefrom.

The several parts of the improved spool or beam are assembled in the manner as next explained. The barrel 2 is first constructed from a flat sheet, punched to form the perforations or openings 6, and rolled into cylindrical form with its edges joined by butt-welding, preferably electrically. The fixed flange or head 4 is next mounted on 40 the end-closure 1 and the latter placed against the end of the barrel 2 with its annular flange 8 underlying the rim of the barrel. An electrical weld is then made by causing the metal to flow into the V-shaped opening 16 between the inner 45 beveled rim 15 of the head 4 and the beveled seat 14 on the member 1. The metal flowing onto the barrel 2 also bonds the latter to its seat on the shouldered flange 8.

The threaded neck 25 is inserted through the 50 axial opening 26 in the disk 20 and welded in place in the manner as previously explained. The disk 20 is then inserted into the end of the barrel 2 and welded into place by flowing the metal into the channel formed between the beveled rim 55 of the disk and the inner periphery of the barrel. With the parts assembled in this manner the head 5, which has a central opening corresponding in diameter to the outer periphery of the neck 25, may be placed on the neck and 60 clamped against the end of the barrel 2 by means of the hand-nut 28.

In practice, the method of utilizing the present improved spool or beam for dyeing and other fluid processing of textile materials and the like is as next explained. For example, in wool top dyeing the head 5 is removed from the end of the spool and the material placed around its barrel in the form of a cylindrical mass. Usually, the spool is stood upright while the mass is placed 70 thereon and pressed down against the fixed head 4, and thereafter the removable head 5 is slid onto the neck 25 and the hand-nut 28 applied in place. By screwing the hand-nut 28 onto the neck 25 75 the material may be compressed between the end

heads 4 and 5 to bring it into a mass of substantially uniform density.

The spool with its surrounding mass of material may then be placed in a dyeing chamber or kier with the end-closure 1 attached to a 5 suitable supply orifice through which the dye liquor is forced. Usually, the opening in the neck 25 is closed by means on the cover of the kier, or otherwise, which also serves to hold the hub 9 of the end-member 1 seated around the supply 10 orifice. The fluid issuing through the opening in the end-member 1 under pressure is caused to flow through the perforations 6 to penetrate the mass of material surrounding the barrel 2. In other cases the direction of flow of the fluid may 15 be reversed to cause it to penetrate the mass from the outside and exhaust through the perforations 6 to be discharged down through the opening 10 in the member 1 at the end of the barrel.

It will be observed from the foregoing that the 20 present invention provides an extremely stanch and rugged structure of spool or beam for use in dyeing and other processing treatment of textile and like materials. The interfitting of the parts and their cooperative relationship provide 25 for welding the joints with a minimum of operations, and the ingenious method of forming the several elements of the spool from sheet-metal conserves the material to further reduce the cost.

While the invention is herein shown and de- 30 scribed as embodied in a preferred form of construction it is to be understood that various modifications may be made in the structure and arrangement of the parts of the spool without departing from the spirit or scope of the invention. 35 Therefore, without limiting myself in this respect, I claim:

1. A metal spool, beam or the like comprising a tubular barrel, a closure-member having an annular flange projecting within the rim of the 40 barrel at the end thereof, said flange formed with a shoulder abutting the edge of the barrel and having a radial dimension substantially equal to the thickness of the latter, said flange having an annular seat adjacent said shoulder with a second 45 shoulder extending radially therefrom, and a head comprising a metal disk having an opening with its rim surrounding the annular seat on the closure-member, said head, closure and barrel secured together in an integral structure by a 50 single weld with the metal flowed around the joint between the head and the annular seat on the closure-member and overlying the rim of the barrel to secure the latter to its shouldered seat.

2. A metal spool, beam or the like comprising a 55 tubular barrel, a closure-member having an annular flange projecting within the rim of the barrel at the end thereof, said flange formed with a shoulder abutting the edge of the barrel and having a radial dimension substantially equal to 60 the thickness of the latter, said flange having an annular seat adjacent said shoulder with a second shoulder extending radially therefrom, and a head comprising a metal disk having an opening with its rim enclosing the annular seat on the 65 closure-member and forming a V-shaped channel between the rim and seat, said head, closure and barrel secured together in an integral structure by a single weld with the metal flowed into the channel between the rim of the head and the seat on the closure-member and overlying the 70 rim of the barrel.

3. A metal spool, beam or the like comprising an annular tubular barrel, a closure-member having an annular flange projecting within the 75

rim of the barrel at one end thereof, said closure-member formed with a shoulder abutting the edge of the barrel and an annular seat with a second shoulder extending radially therefrom, a head 5 formed with a central opening fitted to the annular seat on the closure-member and abutting the radial shoulder thereof, said head, closure-member and barrel being united by a single weld with the metal flowed over the joints therebetween, a metal disk fitted within the opposite end of the barrel and welded thereto, a neck 10 extending axially from said disk, a head having a central opening fitted to slide over said neck to position it in abutting relation with the end of the barrel, and means for detachably fastening said head in position on the neck.

4. A metal spool, beam or the like comprising a tubular barrel, a closure-member having a flange projecting within the rim of the barrel at one end thereof, said member having an annular seat with a shoulder extending radially therefrom, a head comprising a metal disk with an opening at its center fitted to the annular seat on the closure-member in abutting relation to the radial shoulder thereof, said head, closure-member and barrel being secured in an integral structure by a single weld with the metal flowed around the joints of said parts, a disk having a beveled rim engaging the inner rim of the barrel at its opposite end and welded thereto with the metal flowed into the channel formed by the beveled rim of the disk, a tubular neck inserted through an axial opening in the disk and welded in position therein, said neck formed with screw threads, a head having an opening fitted to the neck, and a nut screwed onto the neck to clamp the head against the end of the barrel.

5. A metal spool, beam or the like comprising a

tubular barrel, a closure-member having an annular flange fitted to the inner periphery of the barrel at the end thereof, said flange formed with a shoulder abutting the edge of the barrel and having a radial dimension substantially equal to the thickness of the latter, said flange having an annular beveled seat adjacent said shoulder with a second shoulder extending radially therefrom, and a head comprising a metal disk having an opening with a beveled rim fitted to the beveled seat on the closure-member to form a V-shaped channel therebetween, said head, closure and barrel secured together in an integral structure by a single weld with the metal flowed into the channel between the beveled rim of the head and the beveled seat on the closure-member and overlying the rim of the barrel.

6. A metal spool, beam or the like comprising an annular tubular barrel, a closure-member having an annular flange projecting within the rim of the barrel at one end thereof, said closure-member formed with a shoulder abutting the edge of the barrel and an annular seat with a second shoulder extending radially therefrom, a head formed with a central opening fitted to the annular seat on the closure-member and abutting the radial shoulder thereof, said head, closure-member and barrel being united by a single weld with the metal flowed over the joints therebetween, the central disk portion of the annular head being fitted within the opposite end of the barrel and welded thereto, a neck extending axially from said disk, a head having a central opening fitted to slide over said neck to position it in abutting relation with the end of the barrel, and means for detachably fastening said head in position on the neck.

JOHN M. WOOD.
